Knowles Loom Works, Worcester, Mass., a cor-
poration of Massachusetts

Application January 28, 1935, Serial No. 3,734

20 Claims. (Cl. 139—232)

This invention is a continuation in part of our copending application Serial No. 665,157, filed April 8, 1933.

This invention relates to multicolor shuttle changing looms and it is the general object of the invention to provide a durable selector mechanism to coordinate the operation of the shuttle changing devices with the depleted shuttle.

In the type of loom to which our invention more particularly relates there are shifting shuttle boxes at one end of the loom to bring into play a plurality of shuttles any one of which may remain active as long as desired. It is an important object of our invention to provide a controller moved in timed relation with the shifting shuttle boxes though not necessarily connected to the boxes and having a set of controller latches, one for each shuttle box, which receive and store indications of weft depletion. A regularly moving actuator dog is directed into lifting relation with the lifter lever by the control elements, but the latter are so controlled that only one can engage the actuator dog at a time. Each control element will remain in indicated position until it effects a shuttle change, after which it is reset to normal position.

The latches as heretofore constructed have been held in normal position yieldingly and as a result it has been possible for them to be accidentally moved to an improper setting. It is a further object of our invention to provide lock elements which positively hold the latches against movement to indicating position until released by a feeler indication. We attain this result by causing the device which moves the latches first to rock a lock element to unlocking position, after which the released latch is moved to indicating position.

It is a further object of the invention to provide a setting device such as a solenoid to act for all the shuttles to place the correct control latch in operative position with respect to the actuator dog. The structure set forth herein is more particularly adapted for use in connection with looms of the type set forth in copending applications Serial Nos. 9845; 667,464; 460,746; 747,358; and 665,140 filed by Turner, but is not necessarily limited to use with the weft detector at the magazine end.

The aforesaid applications show a loom operating with shuttle magazine controlling hooks which are positioned by a device moving in time with the shifting shuttle boxes. It is a further object of our invention to connect the control device for the hooks with the carrier for the

latches to insure registry of the latches, magazine compartments and shifting boxes.

In former constructions the regularly moving actuating dog has been acted upon directly as the result of weft detector operation, and it was necessary to hold the latch in abnormal position until lifting of the box rod for the magazine was started. Furthermore, special mechanism was needed to release the latch after transfer was completed. It is a still further object of our invention to set the control latches for the dog independently of the latter and also reset said devices by simplified means. These controls are preferably operated mechanically, although the initial force to set them may be an electro-magnetic device.

With these and other objects in view which will appear as the description proceeds, our invention resides in the combination and arrangement of parts hereinafter described and set forth in the claims.

In the accompanying drawings, wherein a convenient embodiment of our invention is set forth,

Fig. 1 is an end elevation of the lower part of a loom with our invention applied thereto,

Fig. 2 is a detail plan view looking in the direction of arrow 2, but on an enlarged scale,

Fig. 3 is a vertical section on line 3—3, Fig. 2,

Fig. 4 is a vertical section on line 4—4, Fig. 2,

Fig. 5 is a detail similar to part of Fig. 4, showing the manner of unlocking the latch, and

Fig. 6 is a detailed perspective view showing the upper end of the dog which co-acts with the controllers at the time of shuttle change.

Referring to the drawings, the bottom part 10 of the loom frame has mounted thereon a fixed stud 11 on which are pivoted a regularly moving actuator lever 12 and a normally inactive lifter lever 13. Lever 12 carries a roll 14 located in groove 15 of a cam 16 secured to the bottom shaft 17 of the loom and rotating once for every two picks of the loom. The forward end of lever 12 has pivoted thereto an actuator dog 18 movable about pivot 19 against spring 20 which normally holds the dog against stop screw 21, see Fig. 3. The upper end of the dog is pointed and has an upper inclined surface 22.

The normally stationary lever 13 has a lug 23 forming a downwardly opening notch 24 with a surface 25 inclined down and away from lever 13. The forward end of the latter is connected to a shuttle changer box lifter rod 26 by the mechanism indicated at the left of Fig. 1 and forming no part of our present invention. It is sufficient to state that when the box rod 26 rises

with the forward end of lever 13, the change box on the lay, not shown, is set to receive a shuttle from the magazine.

The rear part of lifter lever 13 carries an adjustable stud 27 to cooperate with hooks 28 and 29 located respectively behind and in front of a rockable lever 30. The latter moves about pivot 31 fixed to an arm 32 of a stand 33 secured to fixed stud 11, and has a depending arm 34 movable by a connector 35 attached to a part moving in timed relation with the shifting boxes at the other end of the loom. The connector has a flexible part drawn around a guide pulley 36 rotatable on another arm 37 of stand 33. The lever 30 therefore moves in timed relation with the shifting boxes, and moves one or the other of the hooks into the path of stud 27. This part of the structure may be similar to that shown in application Ser. No. 747,358 filed 20 by Turner.

The matter thus far described forms no part of our invention and may be constructed and operated as shown in the aforesaid applications.

In carrying our invention into effect, we provide the normally stationary lifter lever 13 with an upstanding horn 40 and mount thereon a solenoid 41 having a vertically movable core 42. This solenoid is energized by the detector when indicating weft exhaustion. When the core is lifted by the solenoid a link 43 causes rocking of a setting lever 44 (Fig. 2) pivoted on a pin 45 which extends between and is supported by arms 46 and 47 on lever 13. Lever 44 has an unlocking finger 48 (Fig. 4) which can lie under either of two lock elements 49 or 50 pivoted to dog controlling latches 38 and 39, respectively. The latches are pivotally mounted on a pin 51 in a yoke 52, and the latter slides on a second pin 54 extending between and secured to arms 46 and 47. Lateral motion of the latches relatively to the yoke is prevented by forming them with hubs 55 which contact with each other and the sides 56 of the yoke. The pins 45 and 54 in the arms 46 and 47 constitute a guide frame 45 for the sliding yoke 52, and an extension 58 of side 56 extends partly around pin 45 to hold the yoke in horizontal position.

A rigid rod 60 has its forward end pivoted to an ear 61 on the yoke and is attached at its rear end to lever 30, as by a clip 62. As lever 30 rocks from one position to the other the yoke is caused to slide along the pins 45 and 54. As shown in Fig. 2 lock element 49 is over the finger 48, but upon shifting of the boxes, rod 60 will pull the slide rearwardly to place element 50 over the unlocking finger 48.

Each latch has a rod 65 pivoted thereto and passing through a cross bar 66 on the yoke. A compression spring 67 around each rod urges the latter to move away from cross bar 66 and holds the right ends of the locking elements as viewed in Fig. 5 against a stop pin 59 carried by the yoke. The dog controlling latches 38 and 39 are provided with downward extensions 70 and 71, respectively, each having an inclined lower face 72 movable to dog controlling position. Each latch extension has a stop screw 74 so placed that it can engage a second stop pin 69 carried by the yoke.

A small bracket 75 (Fig. 1) is secured to the loom frame and has a resetter or spring arm 76 (Fig. 3) so placed that it will engage a rounded surface 78 on a latch in indicating position as the lever 13 rises to effect shuttle change.

The relation of the lock element and corre-

sponding latch is set forth more particularly in Fig. 5. Each lock element is pivoted to its latch as at 79 and is normally held against a stop 80 on the latch which limits movement of the lock element under action of a light compression spring 81 interposed between the latch and its lock element. When finger 48 rises it moves the lock against spring 81 and away from stop pin 59. The force of springs 67 is always directed below the rod 60, hence the springs are operative as soon as a lock element is moved to unlocked position to move the corresponding latch into controlling position relatively to the dog 18. Should the latch stick, however, the lock element will engage a surface 82 on the latch 15 and positively move the latch toward indicating position as the finger 48 continues to rise.

Under normal conditions, when sufficient weft is present in the weaving shuttles, lever 12 rises periodically with the lifter dog 18 out of line 20 with the lug 23, and lever 13 will therefore remain down as the dog rises with actuator lever 12. The yoke will change its position in timed relation with the boxes, preferably by a pattern or cam control exercised prior to actual box 25 change, so that first one and then the other of the lock elements 49 and 50 will be over finger 48. As weaving continues the weft supply in the shuttles will become depleted, and the first to reach this condition will indicate through the 30 weft detecting mechanism and cause energization of solenoid 41. This will result in a rocking of lever 44 to lift the lock element which happens to be over the finger 48. As shown in Fig. 4 the element 50 has been raised.

The springs 67 are normally effective to hold their associated locks against the stop pin 59 and upon movement of the lock 50 by the finger 48 away from the pin 59, the corresponding spring 67 rocks the latch 39 to the position shown 40 in Fig. 4. From this it will be seen that the arm 48 does not necessarily give the latches the full motions but serve merely to unlock them. As shown in Fig. 4, the latch 39 is positioned by engagement of the corresponding stop screw with 45 the pin 69.

If the indicating shuttle remains active there will be no sliding on the part of the yoke 52 and at the next upward movement of the actuator lever 12, surface 72 on the latch in indicating 50 position will engage the surface 22 of the dog 18 and direct the latter into notch 24. Under these conditions the dog is moved from the full to the dotted line position shown in Fig. 4. Continued upward movement of the actuator lever thereupon raises the forward end of lever 13 and the rod 26 is elevated to effect change of shuttles. At the same time the stud 27 at the rear of lever 13 is lowered to engage one or the other of the hooks 28 or 29 to release a shuttle from the magazine.

Should a delay in transfer be necessary due to shifting of boxes at the opposite end of the loom there will be a corresponding sliding movement of the yoke so that the latch corresponding to the 65 depleted shuttle will move out of the path of the dog 18 and the latter will move from the full to the dotted line position shown in Fig. 3 without raising the rod 26. A latch or guide member in indicating position but out of line with the dog 70 will remain set until the shuttle corresponding thereto is restored to action regardless of the number of picks laid by the active shuttle. As soon as the boxes shift to return the depleted shuttle to action the corresponding sliding move- 75

ment of the yoke will bring the indicated latch into alignment with the dog 18, and the operation already described in connection with Fig. 4 will ensue.

- 5 It is thus possible to indicate for a change by a depleted shuttle and then move this shuttle out of action and exchange the next shuttle which comes into action without loss of the first indication. In this way we are able to store an 10 indication and retain the same until the proper time to complete the change which is initiated by the weft detector without requiring the latter to repeat its indication.

As the levers 12 and 13 approach the upward 15 limit of their movement the rounded part 78 of a raised latch which happens to be placed to coact with the dog will be reset by the spring 76. It should be noted that this resetting device is out of alignment with any latch which has been shifted out of operative position relative to the dog.

The upper end of the lifting dog is shown in Fig. 6 from which it will be seen that the surface 22 which effects the camming of the dog into the notch 24 is narrow so that a comparatively 20 small end shift of the yoke will take said surface 22 out of the range of one or the other of the surfaces 72 on the bottoms of the latches. That part of the dog which does the actual lifting and is designated at 90 may be as large as is needed 25 to transmit the force required to lift the changing boxes. When the parts are in the position shown in Fig. 4 the surface 22 will rise without contacting with any latch which may be in indicating position, such as 71, but not aligned with the lifting finger 48. The purpose of this is to permit 30 the retention of an indication and to render the resetter 76 operative only with respect to the latch which causes upward movement of the levers. It will be seen by an inspection of Fig. 4 35 that the lower end of a latch in raised position is free to move to the right during the resetting operation without being restrained in any way by the dog or any other part of the mechanism.

During the resetting already described in connection with the resetter 76 the upper right surface of the lock element as viewed in Fig. 5 will move under the stop pin 59 until it clears the latter, whereupon the spring 81 will rock the lock element from the dotted to the full line position 50 shown in Fig. 5 and the parts will be reset with the latch positively locked against improper or accidental indicating movement.

From the foregoing it will be seen that lever 30 acts as a controller to position the yoke and 55 also the hooks which each lead to a different delivery stack in the shuttle magazine. The indicating mechanism includes a set of latches movable to register with the dog one at a time and each movable to a position to guide the dog 60 into driving position relatively to the lifter lever. It will also be seen that the solenoid is carried by the normally stationary lifter lever so that the electrical connections will be subjected to as little movement as possible. Furthermore, the 65 upward movement of the box lifter lever 13 acts to reset the latches and their locking elements. Also, the mechanism for storing the indication comprises separate latches which are given an indicating movement independently of the dog 70 and therefore the latter is free to respond to the control of the latches, regardless of the order in which shuttle changing is effected relatively to the order of exhaustion in the weaving shuttles. Furthermore, the locks prevent accidental 75 movement of the latches toward indicating posi-

tion and are so constructed and controlled that they each automatically restore themselves to locking position when a latch is reset.

Having thus described our invention it will be seen that changes and modifications may be made therein by those skilled in the art without departing from the spirit and scope of the invention and we do not wish to be limited to the details herein disclosed, but what we claim is:

1. In a multi-shuttle shuttle changing loom operating with a plurality of weaving shuttles any one of which may become active, a changing member to be moved to effect shuttle change, a normally stationary lever connected to the member, a solenoid mounted on said lever to be energized upon depletion of weft in the active shuttle, a regularly oscillating actuating lever, a dog carried by the actuating lever and movable into engagement with the first named lever, and a plurality of separate dog controlling latches, one for each weaving shuttle, to be under control of the solenoid one at a time and each effective to move the dog into driving relation with respect to the normally stationary lever. 10 15 20

2. In a multi-shuttle shuttle changing loom operating with a plurality of weaving shuttles anyone of which may become active, a normally stationary changing member to be moved to effect shuttle change, a regularly moving actuator member, a dog on one of said members to engage the other to cause movement of the normally stationary member by the actuating member, said dog normally in such position as to be incapable of transmitting force from one member to the other, and a plurality of devices mounted on one of said members, one for each weaving shuttle, each device capable of being set to establish driving connection between the members through the dog. 25 30 35

3. In a multi-shuttle shuttle changing loom operating with a plurality of weaving shuttles any one of which may become active, a normally stationary changing member to be moved to effect shuttle change, a regularly moving actuator member, a dog carried by one of said members normally out of engagement with the other member, a plurality of dog controlling elements carried by one of the members, one element for each weaving shuttle, the elements being capable one at a time of guiding the dog so as to establish driving connection between the members, and operating means effective upon exhaustion of weft in the active shuttle to set the controlling element corresponding to the active shuttle into operative position relatively to the dog. 40 45 50 55

4. In a multi-shuttle shuttle changing loom operating with a plurality of weaving shuttles any one of which may become active, a normally stationary lever to be moved to effect shuttle change, a regularly moving actuator lever, a dog mounted on and movable relatively to one of the levers to have engagement with the other lever to establish driving connection between the levers, a set of controlling elements slidably mounted on one of the levers, the elements being capable one at a time of cooperating with the dog to cause the same to establish driving connections between the levers, and means dependent upon which of the weaving shuttles is active to shift the set of controlling elements to cause register of the element corresponding to the active shuttle with 60 65 70 75 the dog.

5. In a multi-shuttle shuttle changing loom operating with a plurality of shifting shuttle boxes to render any one of a plurality of weaving shuttles active, a normally stationary lever to be moved 75

- to effect shuttle change, a regularly moving actuator lever, a dog carried by one of said levers and movable to a position to establish driving connection between the levers but normally out of said position, a set of control elements for the dog movably mounted on one of the levers and shifting in timed relation with the shifting shuttle boxes so that said control elements register one at a time with the dog, and means operative upon indication of weft exhaustion in the active shuttle to move the control element corresponding to the active shuttle into position to engage the dog to cause the latter to establish driving connection between the levers.
15. 6. In a multi-shuttle shuttle changing loom operating with a plurality of shifting shuttle boxes to render any one of a plurality of weaving shuttles active, a normally stationary lever to be moved to effect shuttle change, a regularly moving actuator lever, a dog carried by one of said levers and movable to position to establish driving connection between the levers but normally out of said position, a set of control latches for the dog normally in non-indicating position, means to move the set of latches so that the latter will register one at a time with the dog, the latter being out of operative relation with respect to any latch in non-indicating position, means effective upon exhaustion of weft in the active shuttle to move the latch corresponding thereto into indicating position, the indicating latch which is also in register with the dog thereafter engaging the latter to move the same to a position to establish driving connections between the levers, and means to reset the control latch which is in indicating position and in register with the dog to non-indicating position.
7. In a multi-shuttle shuttle changing loom operating with a plurality of shifting shuttle boxes to render any one of a plurality of weaving shuttles active, a normally stationary lever to be moved to effect shuttle change, a regularly moving actuator lever, a dog carried by one of said levers and movable to position to establish driving connection between the levers but normally out of said position, a set of control latches for the dog normally in non-indicating position, means to move the set of latches so that the latter will register one at a time with the dog, the latter being out of operative relation with respect to any latch in non-indicating position, means effective upon exhaustion of weft in the active shuttle to move the latch corresponding thereto into indicating position, the indicating latch which is also in register with the dog thereafter engaging the latter to move the same to a position to establish driving connections between the levers, and means effective during movement of the levers to reset to non-indicating position the latch which is in indicating position and also in register with the dog.
8. In a multi-shuttle shuttle changing loom capable of changing shuttles of different characters of filling by mechanism including a pair of hooks shiftable in accordance with the change of active weaving shuttle, a normally stationary lever movable to actuate one or the other of the shiftable hooks, a regularly moving actuator lever, a force transmitting member carried by one of said levers and movable to a position to establish driving connections between the levers but normally out of said position, a plurality of control elements normally in non-indicating position, a controller for the elements and hooks to move the elements one at a time in register with the member in accord-

ance with the position of said shiftable hooks, and means effective upon indication of weft exhaustion in the active shuttle to move the control element corresponding to the active shuttle from non-indicating to indicating position, a control element in indicating position and also in register with the force-transmitting member being effective to position the latter to establish driving connection between the levers.

9. In a multi-shuttle shuttle changing loom operating with a plurality of shuttles any one of which may become active, a normally stationary lever to be moved to effect shuttle change, a regularly moving actuator lever, a dog carried by the latter lever and movable to a position to move the first named lever but normally out of such position, a yoke slidable on the first named lever, a plurality of control elements on the yoke, one for each of the shuttles which may become active, said elements normally being in non-indicating position and movable one at a time into register with the dog, depending upon which shuttle is active, and means to move the element corresponding to a depleted active shuttle from non-indicating to indicating position, an element in indicating position when in register with the dog being effective to move the latter to establish driving connection between the levers.

10. In a multi-shuttle shuttle changing loom operating with a plurality of weaving shuttles any one of which may become active, two members to be coupled together, one of which is normally at rest and the other of which has an operating movement, means to connect the members together, a controller for each of the weaving shuttles movable to indicating position upon occurrence of weft exhaustion in the corresponding shuttle, said controllers being capable one at a time of having operative relation with respect to the connecting means, a lock to hold each controller against movement toward indicating position, and weft controlled means to move the lock to unlocking position and thereafter move the corresponding controller toward indicating position.

11. In a multi-shuttle shuttle changing loom operating with a plurality of weaving shuttles any one of which may become active, two members to be coupled together, one of which is normally at rest and the other of which has an operating movement, means to connect the members together, a set of controllers for the connecting means movable so that but one controller can be in controlling relation with respect to the means at a time, a lock to hold each controller in non-indicating position, and weft controlled means to unlock the controller corresponding to a shuttle giving indication of weft exhaustion, and thereafter effective to move a controller which is unlocked toward indicating position.

12. In a multi-shuttle shuttle changing loom operating with a plurality of weaving shuttles any one of which may become active, two members to be coupled together, one of which is normally at rest and the other of which has an operating movement, means to connect the members together, a set of controllers for the connecting means movable relatively to the latter so that but one of said controllers is capable of cooperation with said means at a time, yielding means tending to move each controller into indicating position, a lock for each controller to prevent the yielding means from moving the controller to indicating position, and weft controlled means to move the lock to unlocking position.

13. In a multi-shuttle shuttle changing loom operating with a plurality of weaving shuttles any one of which may become active, two members to be coupled together, one of which is normally at rest and the other of which has an operating movement, means to connect the members together, a set of controllers movable laterally relatively to the connecting means so that but one controller is capable of co-action with said means 5 at a time, yielding means tending to move each controller toward indicating position, a lock operatively connected to each controller and the corresponding yielding means to prevent the latter from moving the controller toward indicating 10 position, and weft controlled means to move the locks one at a time to unlocking position.

14. In a multi-shuttle shuttle changing loom operating with a plurality of weaving shuttles any one of which may become active, two members to be coupled together, one of which is normally at rest and the other of which has an operating movement, means to connect the members together, a set of controllers for the connecting means, yielding means tending to move each controller toward indicating position to be operatively 15 relatable to the means, a lock for each controller to prevent the yielding means for moving the controller to indicating position, a weft controlled releaser for the locks, and means to move the locks relatively to the releaser so that but one lock is capable of operative relation with respect 20 to the releaser at a time.

15. In a multi-shuttle shuttle changing loom having a plurality of shuttles each capable of being 25 coming active, actuating means normally having an idle stroke but capable of having a working stroke to assist in a shuttle changing operation of the loom, a plurality of controller elements each capable of causing the actuating means to 30 have a working stroke, a lock to hold each controller element against movement to a position where it can cause the actuating means to have a working stroke, and weft controlled means to move a selected lock to unlock its controller element and to thereafter move said controller element to operative position with respect to said 35 actuating means.

16. In a multi-shuttle shuttle changing loom having a plurality of shuttles each of which is capable of being active, a member to be moved from idle to working position to assist in a shuttle changing operation of the loom, selecting mechanism including a plurality of controllers for the member, lock means to hold said controllers normally out of indicating position, weft controlled means to move a selected lock to unlock the controller corresponding to the active shuttle when the latter is substantially exhausted of weft, and 40

means to cause an unlocked controller to become operatively related to the member to cause the latter to move to working position.

17. In a multi-shuttle shuttle changing loom having a plurality of shuttles each of which may become active, a member to move from idle to working position to assist in a shuttle changing operation of the loom, a set of controllers for the member, locks to hold the controllers in such a position that they are incapable of effecting movement of the member to working position, weft controlled means to move a selected lock to unlocking position, and means to reset the locks and controllers in positions incapable of affecting the position of the member. 15

18. In a multi-shuttle shuttle changing loom having a plurality of shuttles each of which may become active, a member to move from idle to working position to assist in a shuttle changing operation of the loom, a set of controllers for the member, locks to hold the controllers in such a position that they are incapable of effecting movement of the member to working position, weft controlled means to move a selected lock to unlocking position, and means to reset the locks 20 and controllers in positions incapable of affecting the position of the member, said resetting means being rendered operative by a force transmitted through the member. 25

19. In a multi-shuttle shuttle changing loom, a member normally in idle position but movable to working position to assist in a shuttle changing operation of the loom, a set of controllers each movable from normal to indicating position, the controller corresponding to the active shuttle when 30 in indicating position being capable of effecting movement of the member to working position, and a resetter for the controllers to cooperate with a controller in indicating position, said member 35 when in working position causing relative motion 40 between the resetter and the operative controller to effect resetting of the latter.

20. In a multi-shuttle shuttle changing loom having a plurality of weaving shuttles each of which may become active, a member movable from idle to working position to assist in a shuttle changing operation of the loom, a resetting device, a plurality of controllers for the member movable between the resetter and the member, means to move the controllers from normal idle 45 to indicating position, means to cause cooperation between the controllers one at a time and the member and resetter, the member causing relative movement between the controller cooperating therewith and the resetter to effect resetting of 50 said controller. 55
